UNITED STATES PATENT OFFICE.

MORRIS LEVITAN, OF NEW YORK, N. Y.

DESIGN FOR A SCROLL ARM FOR ELECTRIC-LIGHTING FIXTURES.

Application filed September 28, 1925. Serial No. 14 922. Term of patent 3½ years.

To all whom it may concern:

Be it known that I, MORRIS LEVITAN, a citizen of the United States, residing at No. 868 Faile Street, borough of Bronx, city and State of New York, have invented a new, original, and ornamental Design for a Scroll Arm for Electric-Lighting Fixtures, of which the following is a specification, reference being had to the accompanying drawing, forming a part thereof.

The figure shows a side view of my design for a scroll arm for electric-lighting fixtures.

I claim:—

The ornamental design for a scroll arm for electric-lighting fixtures, as shown.

MORRIS LEVITAN.
